DESIGN FOR A CHRISTMAS TREE STAND

Howard R. Parman, Chicago, Ill., assignor to Chamberlain, Inc., Chicago, Ill., a corporation of Illinois

Application May 18, 1940, Serial No. 92,450

Term of patent 14 years

To all whom it may concern:

Be it known that I, Howard R. Parman, a citizen of the United States, residing at Chicago, Cook County, Illinois, have invented a new, original, and ornamental Design for a Christmas Tree Stand, of which the following is a specification, reference being had to the accompanying drawing forming part thereof.

Fig. 1 is a top plan view of a Christmas tree stand, showing my new design, it being understood that the ornamentation partly shown in this view is applied to the entire upper portion of the article within the limits indicated; and Fig. 2 is a side elevational view thereof.

I claim:

The ornamental design for a Christmas tree stand, as shown and described.

HOWARD R. PARMAN.
